UNITED STATES PATENT OFFICE.

HARRY A. COCHRAN, OF HOUSTON, TEXAS, ASSIGNOR TO AMERICAN AUTOMATIC WATER HEATER CO., DOING BUSINESS IN TEXAS, A CORPORATION OF ARIZONA.

GAS-VALVE.

1,156,347.

Specification of Letters Patent.

Patented Oct. 12, 1915.

Application filed December 2, 1913. Serial No. 804,308.

To all whom it may concern:

Be it known that I, HARRY A. COCHRAN, a citizen of the United States, residing at Houston, in the county of Harris and State 5 of Texas, have invented certain new and useful Improvements in Gas-Valves, of which the following is a specification.

This invention relates to new and useful improvements in a gas valve and has more 10 particular relation to a valve of the character specified which is adapted to be used in connection with a water heater and which is arranged so as to be automatically opened by the water current through the water pipe 15 so as to admit gas to the burner when water is drawn off from the water pipe and a current is thus created in said pipe.

A further feature of the invention resides in the provision of means whereby said valve 20 is automatically closed and gas is shut off from the burner when the spigot through which the water is drawn from the water pipe is closed and the current through said pipe stopped.

With the above and other objects in view, the invention has particular relation to certain novel features of construction, operation and arrangement of parts, an example 25 of which is given in this specification and 30 illustrated in the accompanying drawings, wherein—

Figure 1 is a sectional side elevation of the ordinary water heater, showing the connecting gas and water pipes and showing 35 a side elevation of the valve in connection therewith. Fig. 2 is a plan view of the valve. Fig. 3 is a sectional side elevation thereof. Fig. 4 is an enlarged fragmentary 40 sectional side elevation thereof. Fig. 5 is a bottom view thereof. Fig. 6 is an edge view of the gate which operates the valve. Fig. 7 is a side elevation thereof. Fig. 8 is a plan view of a metallic plate in which 45 the upper end of the gate shaft has a bearing. Fig. 9 is a plan view of the nut which operates the valve proper, showing the operative spring in connection therewith, and Fig. 10 shows a bottom plan view of the 50 nut holding the stuffing box of the gate shaft in position.

Referring now more particularly to the drawings, wherein like numerals of reference designate similar parts in each of the figures, the numeral 1 refers to the ordinary water heater having the coil pipe 2 therein 55 which is supplied from the water pipe 3 and from which leads the draw-off pipe 4, from which water may be discharged through either of the spigots 5, 5, 5, which may be located in different parts of the building. 60 In the heater 1, underneath the coil 2 is the gas burner 6 which is supplied with fuel through the gas pipe 7. The flow of gas through this pipe is controlled by the valve 8, which in turn is opened by the water 65 current through the pipe 3, which is set up when water is drawn off through one of the spigots 5. The water supplying the building is delivered from a suitable source of supply through the supply pipe 3' and 70 passes through the cylindrical chamber 9 into the pipe 3 and the gas consumed is delivered from the source of supply through the supply pipe 7' and passes through the cylindrical chamber 8 into the pipe 7. The 75 chambers 8 and 9 are made integral by means of the neck 10. This neck has a bearing in which the vertical shaft 11 rotates and carries the stuffing box 12 around said shaft, which is held in position by means of the 80 nut 13. The upper end of the shaft has a gate 14, fixed thereon, formed of two thin metallic plates, with a layer of asbestos or some similar material clamped therebetween and which projects beyond the free edges of 85 said plates on all sides. The chamber 9 has a cap 15 which is screwed over the upper end thereof, the underside of said cap having an asbestos lining 16. A circular metallic plate 17 is provided which has a central 90 orifice 18 in which the upper end of the shaft 11 has a bearing. The rim of the plate 17 rests upon an annular shoulder 19 formed in the upper edge of the chamber wall and said plate is clamped and firmly held in position by means of the cap 15. The gate 14 is of sufficient length to reach to the chamber wall and in width reaches from the top to the bottom of said chamber. The chamber 9 has a partition 20 extending diametrically 95 100

across the same from wall to wall and extending from top to bottom. The supply pipe 3' enters the chamber on one side of this partition and the pipe 3 leads out from the same side, so that the water current passes through said side of said chamber and is partitioned from the other side by the partition 20. The gate 14 is arranged in the chamber so that when a current is set up 10 therethrough the water delivered from the pipe 3' will be delivered in behind said gate and will force the same around to the position indicated in dotted lines in Fig. 2 until the gate clears the outlet of pipe 3 from said chamber and an uninterrupted flow of water 15 will be permitted from one pipe through the chamber to the other pipe. The gate 14 has an orifice 21 therethrough for a purpose to be hereinafter set forth.

20 The lower end of the shaft 11 extends down into the chamber 8 and has the outwardly threaded nut 22 fixed thereon, the lower end of said shaft being square in cross section and extending through a correspondingly shaped hole in said nut and said nut 25 22 being secured on said shaft by means of the lock nut 23. The bottom of the chamber 8 is open but its walls converge inwardly and a circular valve 24 is provided to open 30 and close said lower end of said chamber. This valve has an inwardly threaded socket member upstanding therefrom in which the nut 22 is threaded. The valve 24 is fixed against turning by means of the arms 26, 35 26 which are fixed thereto and whose free ends lock against the shoulders 27, 27 projecting out from the wall of the chamber 9.

When one of the spigots 5 is opened a 40 water current will be created through the water pipes, hereinbefore described, which will force the gate 14 around in the direction indicated by the arrow in Fig. 2, causing a corresponding rotation of the shaft 11 and the nut 22 and operating to force the 45 valve 24 downwardly. As hereinbefore explained, the gas supply pipe 7' communicates with the chamber 8 and when said valve 24 is forced downwardly, the gas passes from said chamber into the pipe 7 and thence to the burner 6. Leading from the chamber 8 is a small gas pipe 28 which 50 conducts a jet of gas into the burner chamber and this jet constantly feeds a small flame which is always burning in said chamber, so that when gas is admitted through the pipe 7 to the burner 6 it is immediately 55 ignited. A strong coil spring 29 is provided in the chamber 8 which surrounds the lower end of shaft 11. The upper end of 60 said spring is secured to the lower end of neck 10 and the lower end of the spring has connection with the nut 22. The current of water operating against the gate 14 is strong enough to turn the shaft 11, over-

coming the tension of said spring 29, but 65 when the water spigot has been closed and the current through the water pipes is stopped the tension of the spring operates to force the gate 14 back to its normal position, the orifice 21 being provided in said 70 gate to permit the water behind the gate to pass therethrough as the gate is moved back to its original position. This operation of the shaft 11 has the effect, through the nut 22 of lifting the valve 24 and shutting off the flow of gas from the chamber 8 to the burners. It is thus obvious that by the use of a valve of this character in connection with the gas supply and water supply pipes, hot water is always available and 80 that the operation of drawing off the water from the pipe for use will automatically result in lighting the gas in the water heater and the heating of the water in the coils of 85 said heater.

What I claim is:—

1. A device of the character described including two chambers, a water inlet and outlet for one of said chambers and a gas inlet and outlet for the other of said chambers, a valve having an internally threaded socket for closing said gas outlet, a means for securing said valve against rotation, a rotatable shaft, one end of which has a threaded connection in said socket and the other end of which projects into the first mentioned chamber, a gate fixed to said shaft and located in the first mentioned chamber, so as to be operated by the current passing therethrough and partially rotate said shaft in one direction, so as to move the valve lengthwise, in one direction relative to the shaft, and a resilient member operatively connected with the shaft and tending to rotate the same in the opposite direction, when the current is cut off and move the valve in the opposite direction. 105

2. A device of the character described including two chambers, a neck connecting said chambers, a water inlet and outlet for one of said chambers and a gas inlet and outlet for the other of said chambers, a circular valve, having an internally threaded socket member upstanding therefrom, a seat with which the valve co-operates to open and close said gas outlet, laterally extending arms carried by said valve and engaging with the seat and securing said valve against rotation, a rotatable shaft, one end of which has a threaded connection in said socket and which extends through said neck and whose other end projects into the first mentioned chamber, a gate fixed to said shaft and located in the first mentioned chamber so as to be operated by the current passing therethrough and partially rotate said shaft in one direction, so as to move the valve 110 115 120 125

lengthwise with respect to the shaft, against said seat, and a coil spring surrounding said shaft and operatively connected therewith and tending to rotate the same in the opposite direction, when the current is cut off, and move the valve, in the opposite direction and from the seat.

In testimony whereof I have signed my name to this specification in the presence of two subscribing witnesses.

HARRY A. COCHRAN.
